LOCATING ABRASIVE WHEELS FOR DRESSING

Elman R. Dunn, Beloit, Wis., assignor to Gardner Machine Company, Beloit, Wis.

Application June 29, 1956, Serial No. 594,863

7 Claims. (Cl. 51—111)

This invention relates to disc grinders particularly double disc grinders and more particularly to means for positioning the abrasive discs in relative longitudinal positions for dressing and for grinding. In machines of this type, the dressing device consists of a diamond holder having oppositely spaced diamonds for simultaneously engaging each of the abrasive discs. During a grinding operation, the discs are spaced to grind a work-piece to a predetermined thickness, length, or width as the case may be. For semi-automatic dressing, it is necessary that the discs be shifted to a spacing equal to the spacing of the diamonds on the dressing tool. After the dressing operation, the discs must be shifted to the proper spacing for grinding.

An object of this invention is to provide means for shifting the discs a predetermined distance between the grinding and dressing positions.

In present machines of this type, the discs are retracted from grinding position against the resistance or pull of a weight or spring which serves as a backlash take-up mechanism to maintain a continuous force in one direction on the supporting members of the discs.

Another object of this invention is to provide this one direction force by means of air pressure.

Figure 1 is a front elevation partly in section and partly cut away to show the means for shifting the heads supporting the abrasive discs between grinding and dressing positions, means for compensating for dressing, and means for controlling the extent of movement of said heads between grinding and dressing positions.

Figure 2 is a hydraulic and electric diagram.

Numeral 10 indicates the bed of a disc grinder on which are slidably mounted for longitudinal movement a pair of head members 11a and 11b having opposed abrasive discs 13a and 13b pivotally mounted thereon.

Since the head members and the means for actuating them are identical, a description of one is considered sufficient. However, suitable reference numerals will be applied to both heads. At the outer end of the head member 11b is mounted a feed mechanism consisting of a housing 20b in which is rotatably mounted a feed screw 21b having a stop pin 22b mounted in the end toward the bed. Said stop pin 22b has a spherical stop surface 23b. A gear 24b mounted on feed screw 21b engages a pinion 25b on shaft 26b. A ratchet wheel 27b also attached to shaft 26b is actuated by pawl 28b which in turn is actuated by means of a piston 32b.

The means for shifting head member 11b to the right for dressing consists of a cylinder 40b mounted in bed 10 and having a piston 41b slidably mounted therein. A piston rod 42b on piston 41b has a spherical stop surface 43b thereon. Spherical surfaces 23b and 43b on stop pin 22b and piston rod 42b respectively are held in a predetermined spaced relation by means of a rod 50b. The length of said rod varies with the thickness of the piece to be ground and determines or is dependent on the distance the member has to move between the grind-

ing and dressing positions. The rod is slidably supported in a pair of bushings 51b and 52b in the wall 53b of bed 10. The outer end of bushing 51b serves as a stop for piston rod 42b and stop member 43b. The outer end of bushing 52b serves as a stop for feed screw stop pin 22b. Thus, movement of piston 41b to the right is transmitted through the piston rod 42b through rod 50b, feed screw 21b and housing 20b to head member 11b.

The means for moving said head member 11b in the opposite direction consist of a cylinder 60b pivotally mounted at 61b in bed 10 and having a piston 62b slidably mounted therein and connected to a piston rod 63b. The lower end of arm 70b is pivotally mounted at 71b. Said piston rod is resiliently connected to arm 70b at an intermediate point. The upper end of arm 70b may be connected by any suitable abutment or linkage to the head member 11b. The head end of cylinder 60b is connected to a continuous supply of air under pressure and this serves as a cushion to the retracting movement of head member 11b.

Operation

Closing the start switch energizes 1CR which completes a circuit through 1CR1 and In-LS to energize valve solenoid C to direct air under pressure to the upper portion of the booster 6. This pressure acts on a body of hydraulic fluid which is directed from the lower end of said booster to the head ends of cylinders 40a and 40b to separate the abrasive discs 13a and 13b mounted on heads 11a and 11b.

Said start switch also closes a circuit to energize valve solenoids A and B to shift valves 3a and 3b, to direct fluid under pressure to the rod end of cylinders 30a and 30b, to actuate the feed pistons and pawls 28a and 28b, to advance each of the abrasive discs in accordance with the amount of abrasive to be removed by the dressing tool as it moves to the In position.

Energizing 1CR completes a circuit through 1CR2, 3LS, and 8LS to energize valve solenoid D. 3LS and 8LS are positioned to be actuated by the two feed mechanisms. Valve solenoid D initiates the operation of the dresser motor 80 to reciprocate the diamond holder 81 across the faces of the abrasive discs 13a and 13b.

As the dresser tool begins its movement to the In position, Out-LS is closed to hold 1CR after the start switch is released, and also to keep valve solenoid C energized which in turn keeps the abrasive discs separated.

When the start switch is released, valve solenoids A and B are deenergized so that pawls 28a and 28b are reset. When the dressing tool reaches the In position, it shifts In-LS to complete a circuit around the start switch to again energize valve solenoids A and B to provide another feed increment of the discs in preparation for the movement of the dresser to the Out position.

The In-LS opens the holding circuit to deenergize 1CR. 1CR2 opens the circuit to valve solenoid D reversing the movement of the dresser and starting it to the Out position.

When the dresser reaches the Out position, it opens Out-LS to deenergize valve solenoid C which reverses the pressure on the booster 6 so that the pressure on the head ends of cylinders 40a and 40b is released and the constant air pressure in the head ends of cylinders 60a and 60b serves to return the heads 11a and 11b and the discs 13a and 13b to grinding position in which they are properly located by engagement of stop surfaces 23a and 23b engaging the co-operating surfaces on the bushings 52a and 52b. The dressing tool stops in the Out position until it is again actuated by closing the start switch.

In actual practice, the start switch is actuated by a counter or some other conventional control device. The

dressing operation is stopped by a similar control. For the purpose of illustration, a simple manually actuated start and stop switch is considered sufficient.

I claim:

1. In a disc grinder, a pair of opposed abrasive discs, each having a spindle and a spindle housing for rotatably supporting said discs in axial alignment, slide members for slidably supporting said spindle housing for movement of said discs between grinding and dressing positions, means for performing a dressing operation on said discs comprising a pair of oppositely disposed dressing tools mounted for movement across the annular surfaces of said discs, means for moving said spindle housing to separate said discs, means to stop said separating movement with said discs spaced by an amount equal to or less than the space between the operative surfaces of said dressing tools including removable stop pins for determining the zone of movement of said housing, the length of said pins being inversely proportional to the distance between the surfaces of said abrasive discs when in grinding position, means for adjusting the space between said discs to compensate for wear and dressing, means for retracting said dressing tools from between said discs after the operation of said dressing means, and means operable at the end of a dressing operation to reset said discs in proper spaced relation for grinding workpieces to a predetermined size including an adjustable stop member movable with said spindle housing.

2. In a disc grinder, a pair of opposed abrasive discs, a separate longitudinally movable support for each of said discs, means for performing a dressing operation on the operative surface of said discs comprising a pair of oppositely disposed dressing tools, means for separating said discs by an amount less than the space between the operative surfaces of said dressing tools, means for adjusting the position of said discs to compensate for wear and dressing, and means to reset said discs comprising positive stops for locating said discs in a predetermined spaced relation corresponding to the thickness of the workpiece to be ground, an adjustable stop member on said longitudinally movable support members for co-acting with said positive stop, and means for actuating said adjustable stop member to compensate for changes in the longitudinal position of said operative surfaces.

3. In a disc grinder, a bed, a spindle housing slidably mounted on said bed, a spindle rotatably mounted therein, an abrasive disc on said spindle, a feed mechanism attached to the end of the slide opposite said disc, said mechanism having a depending portion, an adjustable stop member in said depending portion, means for moving said housing on said bed in an axial direction comprising a cylinder, a piston slidably mounted therein, a piston rod on said piston, connections between said piston rod and said adjustable stop including a pin slidably mounted in said bed, a pair of opposed bushings in said bed for slidably supporting said pin, one of said bushings serving as a positive stop for said adjustable stop member, means for moving said spindle housing in the opposite direction including a cylinder, a piston slidably mounted therein, connections between said piston and said spindle housing, means for maintaining continuous pressure in said cylinder in a direction opposite to the retracting movement of said first mentioned piston to provide a cushion for said retracting movement and to return said spindle housing and abrasive disc to grinding position upon the release of pressure in said first mentioned cylinder.

4. In a grinding machine, a bed, a grinding wheel support slidably mounted on said bed, a grinding wheel

spindle rotatably mounted on said support, an abrasive tool on said spindle, a feed mechanism for moving said tool toward and away from operative position comprising a piston and cylinder, one of which is mounted in said bed, the other of which is connected to said support for moving said support away from operative position, a second piston and cylinder connected to said support for moving it toward operative position, a supply of fluid under pressure connected to said cylinder to urge said piston continuously in a direction opposite to the first mentioned piston whereby to provide a cushion for said retracting movement, and to return said support and said abrasive tool to grinding position upon the release of pressure in said first mentioned cylinder.

5. In a disc grinder, a bed, a spindle housing slidably mounted on said bed, a spindle rotatably mounted in said housing, an abrasive disc on said spindle, means for shifting said spindle housing and disc axially on said bed between a grinding position and a dressing position including a cylinder, a piston slidably mounted therein, a piston rod on said piston, means for stopping movement of said housing in one direction comprising a stop member on said piston rod, a fixed stop in the path of said piston rod, an adjustable stop member on said spindle housing, a fixed stop in the path of said adjustable member to stop the movement of said housing in the opposite direction, and selective means which vary inversely with the thickness of the workpiece to be ground for maintaining a fixed distance between said movable stop members.

6. In a disc grinder, a bed, a spindle housing slidably mounted on said bed, a spindle rotatably mounted in said housing, an abrasive disc on said spindle, means for shifting said spindle housing and disc axially on said bed between a grinding position and a dressing position including a cylinder, a piston slidably mounted in said cylinder, a piston rod on said piston, connections between said piston rod and said spindle housing including a pin slidably mounted in a pair of oppositely disposed bushings in said bed, an adjustable stop on said housing in the path of said pin, said bushings having stop surfaces for engaging said piston rod and said adjustable stop member respectively in dressing and grinding positions, said pin being of a length determined by the thickness of the workpiece to be ground.

7. In a disc grinder, a pair of opposed abrasive discs, each having a spindle and a spindle housing for rotatably supporting said discs in axial alignment, slide members for slidably supporting said spindle housing for movement of said discs between grinding and dressing positions, means for performing a dressing operation on said discs comprising a pair of oppositely disposed dressing tools mounted for movement across the annular surfaces of said discs, means for moving said spindle housing to separate said discs, means to stop said separating movement with said discs spaced by an amount equal to or less than the space between the operative surfaces of said dressing tools including removable stop pins for determining the zone of movement of said spindle housing.
